 signors, by mesne assignments, to Radio Cor-
 poration of America, New York, N. Y., a cor-
 poration of Delaware

Application February 20, 1930, Serial No. 430,053
 In Great Britain March 16, 1929

14 Claims. (Cl. 274—10)

This invention relates to improvements in talking machines and in particular to talking machines of the kind which embody means for automatically reversing a disc record in the playing position so that when the selection on one side of the record has been played the record is turned over to bring the other side into position for co-operation with the reproducer.

The invention is particularly suitable for use with automatic talking machines which play a series of records fed singly in succession from a magazine to the playing position, for when so used, it permits the records fed from the magazine to be played from both sides. It will however be understood that the application of the invention is not limited to use with magazine machines but it may be used with any type of machine employing disc records with sounds recorded on both sides.

Talking machines embodying means for reversing disc records are known in which record engaging members are employed which move the record vertically, the members being also capable of being rotated together with the engaged record for the purpose of reversing it.

According to the present invention there is provided record reversing mechanism of the type having record engaging members adapted to move the record in a vertical direction and to be inverted with the record to reverse it, wherein the reversal of the record and record engaging members is effected during the vertical movement of the record.

In the preferred form, the record engaging members are in the form of pairs of arms pivoted on a carrier and adapted to grip the record between them, the carrier itself being arranged for rotational movements in a bearing at the upper end of a pillar or standard mounted for up and down movements, and being also provided with a toothed wheel which co-operates with a rack or racks on a fixed part of the machine as the pillar or standard moves vertically to effect rotation of the carrier, arms and record.

The record engaging arms on the carrier, during playing, lie one at each side of the record and out of contact therewith. Each arm is formed of two parts which move together about pivots on the carrier. When the record in the playing position is to be reversed the arms are moved inwards or towards one another to a position where the parts of each arm lie one above and one below the record. In this position the record is yieldingly gripped between the parts of the arms and it remains so gripped until the reversing operation

has been completed. When the record to be reversed has been gripped, the carrier, arms and record are first raised, then swung laterally to a position where space is afforded to permit the record to be turned, whereupon the carrier, arms and record are lowered and then raised again. During these lowering and rising movements, the carrier, arms and record are rotated through 180° to bring the unplayed side of the record uppermost, whereupon carrier, arms and record are swung back to the position where the record is over the turntable, and lowered to deposit the reversed record on the turntable ready for reproduction of the selection now uppermost.

The invention is illustrated by way of example in the accompanying drawings as applied to a machine of the kind embodying means for automatically repositioning the sound arm between the completion of playing of one record and the commencement of playing of the next.

In the drawings,

Fig. 1 is a plan view of a part of a talking machine to which the invention has been applied.

Fig. 1A is an enlarged fragmentary detail view of a portion of the mechanism shown in Fig. 1.

Fig. 2 is a plan view of part of a machine with the parts of the record reversing mechanism in position where the reversing operation has been partly carried out.

Fig. 3 is a part side elevation of the machine looking in the direction of the arrow in Fig. 2.

Fig. 4 is a part side elevation corresponding to Fig. 3 but with the parts of the reversing mechanism at rest.

Fig. 5 is a part sectional side elevation on the line 5—5 of Fig. 1.

Figs. 7 and 8 are sectional elevations of the record engaging arms with the parts in the record gripping and non-gripping positions respectively and drawn on a larger scale and on the line 7—7 of Fig. 6.

Figs. 9 and 10 show details.

Fig. 11 is a view in elevation showing the operating cams and associated transmission members.

Fig. 12 is a plan view taken on the line 12—12 in Fig. 11.

Fig. 13 is a plan view on the line 13—13 of Fig. 11.

Fig. 14 is a plan view on line 14—14 of Fig. 11.

Referring to the drawings (Fig. 1) 1 is the base plate of the machine mounted in a suitable cabinet 2. Beneath the base plate 1 is sus-

pended an electric motor 3 which continuously drives a turntable spindle 4 through gearing (not shown) in the usual manner.

The turntable spindle at its upper end supports a turntable 5 of a diameter which is less than that of the smallest record to be employed. A sound arm 6 is pivoted at 7 and carries the usual reproducer 8 at its free end.

A clutch device 9 of known form is provided on the turntable spindle 4 and this device is operated by the known arrangement comprising a pivoted clutch operating lever 10, having a toothed segment 18 pivotally mounted on its outer end which segment co-operates with a ratchet wheel 11 on an arm 12 rigid with the sound arm 6, to put in the clutch when a movement is imparted to the sound arm 6 in the opposite direction to that in which it moves during playing. Such a reversal of the movement of the sound arm may be effected in known manner by the entry of the stylus of the reproducer into an eccentric groove provided at the end of the record sound line near the centre of the record. When the clutch is put in in this manner, the constantly rotating turntable spindle 4 is coupled through suitable gearing 13, 14, 15, 16 (Figs. 1 and 2) with a series of cams carried by a stub shaft 17, which effect the various automatic operations of the machine.

The means described, comprising the shaft 17 and the means for intermittently coupling said series of cams with the machine motor 3 through the turntable spindle 4 each time the playing of a record is completed, are substantially the same as those described in our British Patent No. 317,357 and do not form part of the present invention.

The intermittently driven series of cams are utilized in known manner and as described in the machine forming the subject of the earlier patent to raise the sound arm 6 to disengage the stylus from the record on the turntable, to swing the sound arm 6 outwards to a position where the reproducer is outside the edge of the record, to move the sound arm inwards again until the stylus is over the edge of the record and finally to lower the sound arm 6 to engage the stylus with the surface of the record on the turntable.

In the machine according to the present invention additional cams are provided on the shaft 17, which cams, through suitable transmission mechanism hereinafter described operate record reversing means.

The record reversing means comprises a pair of record engaging arms 25, 26 each of which is formed of two parts an upper and a lower. The two part arms are mounted for movement about separate pivots formed by short tubes 23, 24 mounted in a carrier member 19. The carrier member 19 is formed by bending a piece of sheet metal to form upper and lower plates 20, 21, connected by a web 22 and the short bearing tubes 23, 24 extend through apertures in the upper and lower plates 20, 21, being secured therein by nuts 27 screwed on to the ends of the short tubes. The two parts of each record engaging arm 25, 26 are fixedly secured together by links 28 situated towards the pivoted ends of the arms.

The arms 25, 26 during playing of the machine lie in the positions shown in full lines in Fig. 1. When the record on the turntable is to be reversed the arms are caused to move about their pivots 23, 24 on the carrier into the position indicated in dotted lines in Fig. 1 in which

the upper part of each arm lies above the record on the turntable and the lower part below the record.

The means employed for effecting these movements of arms 25, 26 is as follows:—

Through an aperture in the centre of the web 20 of the carrier 19 extends a sleeve 29 having a flange 30 fitting between the parts 20, 21 of the carrier, and the sleeve 29 is fixed with regard to the carrier 19 by means of a lock ring 31. The sleeve 29 is mounted in ball bearings 32, 33 so as to be capable of rotational movements in a barrel-like member 34 supporting the ball bearings 32, 33 at its ends and itself supported at the upper end of a vertical pillar or standard 35.

Within the sleeve 29 is mounted a rod 36 which is capable of sliding movement therein for a purpose yet to be described and on this rod slides a member 37 shaped as shown in Fig. 10.

The member 37 has lugs 38, 39, 40 and 41 formed on four sides, and in the side lugs 39 and 41 are formed elongated grooves or depressions 42, while an aperture 43 extends vertically through the body of the member 37 and the upper and lower lugs 38 and 40.

The depressions 42 in the side lugs 39, 41 in the mounted position receive vertical pins 44 which are secured between extensions of the upper and lower part of each of the arms 25, 26, one to each arm (see Fig. 6).

The lower end of the aperture 43 receives the ball-shaped end of a lever 45 mounted for movement in a vertical plane about an axis 46 carried on a fixed part of the machine.

The lever 45, the body of which is of channel section, is pivotally connected at its lower end (Fig. 12) to a plate 91 by means of a pin 92 which passes through the walls of lever 45 and the lugs 93 carried by plate 91, the plate 91 being bolted to one end of a horizontal link 47 which is adapted for reciprocating movement of given extent under the influence of a cam 94 on the shaft 17.

The cam 94 is of the double acting type, that is to say, is formed by two profile plates 94' and 94'' which are fixed together, and cooperate with two rollers 47', 47'' which are pivoted on the link 47. Each of said rollers cooperating with one of the said profile plates so that the link 47 is moved positively in either one of two directions.

A slot is provided in the link 47 for engagement with the sleeve 17' carried by the shaft 17 whereby the link 47 is guided in its movements.

When the arms 25 and 26 are to be moved toward one another to engage the record to be turned over, the lever 45 is rocked by the cam 94 link 47 and plate 91 from the position shown in Figs. 4 and 5 to that shown in Fig. 3. In consequence member 37 is caused to slide along rod 36 from the position indicated in the lower half of Fig. 6 to that indicated in the upper half of that figure. By virtue of the engagement of pins 44 in the depressions 42 in the lugs 41 and 39 of member 37, the arms 25 and 26 are moved about the pivots 23, 24 from the position indicated in full lines in Fig. 1 to that indicated in dotted lines in that figure to engage the record.

The arms 25, 26 having been moved into engagement with the record, means are provided to enable the record to be gripped between the parts 70 of the arms so that the record shall remain firmly gripped between the parts throughout the subsequent steps in the reversing operation.

For this purpose the parts of the arms 25, 26 are of shallow trough formation with the in-

terior of the troughs of each pair facing towards each other.

Within each trough (Figs. 7 and 8) is mounted a flat contacting member 48 formed for example of thin metal faced with thin felt and having a short leg 49 at each corner to keep the member 48 away from the bottom of the trough. Between each member 48 and the bottom of the trough is arranged a corrugated leaf spring 50 the end of which abuts against the end wall 51 of the trough while the other end is fixedly connected with a bar 52 also lying within the trough. Pins 53 extend across the trough to retain the spring 50 in position. A light U-shaped wire spring 54 is also mounted in the trough behind the members 48, the bottom of the U being threaded through eyes 55 at the back of the members 48, the arrangement being such that the spring 54 tends to hold member 48 down in the trough 20 with the legs 49 in contact with the trough bottom.

The end of the bar 52 away from the spring 50 is pivotally connected through a common pivot with two links 56 and 57, the former of which is pivoted at a point 58 on the part of the arm 25 or 26, while the other is pivotally connected with the end of the horizontally moving rod 36 (Fig. 5) through a long pin 59 which extends through an aperture in the end of the rod 36 and through the ends of the two links 57 of each arm. The ends of the pin 59 are of ball shape and the lower end engages in a depression in the end of a lever 60 mounted for movement in a vertical plane about a horizontal axis 61 on a fixed part of the machine.

This lever 60 is pivotally connected at the lower end with an angle plate 95 (Figs. 11 and 12) which in turn is bolted to the end of a link 62 arranged to make horizontal reciprocating movements in timed relation with those of link 47 under the influence of the same cam 94 on the shaft 17.

Two rollers 62' and 62'' engage the two connected profile plates 94' and 94'' of cam 94 so that link 62 is always moved positively. A slot in the link 62 engages over the sleeve 17 on the shaft 17 whereby the link 62 is guided, and a slot 100 is formed in the link 47 through which the roller 62' passes to engage the profile plate 94' of the cam 94.

To grip the record on the turntable the lever 60 is moved by the cam 94 and link 62 from the position indicated in Fig. 5 to that shown in Fig. 3. In consequence rod 36 is moved into sleeve 29 and the links 57 are moved through pin 59 from the position represented by the lower half of Fig. 6 to that represented in the upper half of that figure. Bars 52 are thereby thrust longitudinally of the trough shaped parts of the arms 25, 26 and the corrugated springs 50 are caused to bend and shorten and the contacting members 48 are thereby moved away from the bottom of the troughs and into firm contact with the surface of the record 92 to be gripped, in the manner clearly indicated by Figs. 7 and 8.

As the contacting members 48 moved into the record gripping position the record is raised slightly from the turntable surface so that there is no rubbing between the constantly rotating turntable and the now stationary record.

The record having been gripped by the arms 25, 26 the next step consists in raising the record from the turntable to free the central aperture of the record from the turntable spindle 4.

To this end the pillar or standard 35 supporting the barrel-like member 34, the carrier 19 and the connected parts, is itself mounted for vertical movements in a fixed guiding sleeve 63 on a fixed part of the machine. The vertical movements of the pillar or standard 35 in the sleeve 63 are effected by means of a double bell crank lever 64 (Figs. 3, 4 and 11) mounted for rocking movements about a horizontal axis formed by a pin 65 supported in brackets 66 fixed to the exterior of the guide sleeve 63.

The horizontal limbs 67 of the bell crank lever 64 engage pivotally at their ends with trunnions 68 on a disc or washer 69 (Fig. 4), having an enlarged central aperture, and which is connected with the lower end of the pillar or standard 35 through a nut 75 screwed on to a threaded pin 76 extending from a plug 77 in the end of the tubular pillar 35. A friction washer 78 is interposed between the nut 75 and the washer 69 and the arrangement is such that washer 69 is capable of laterally sliding movements with regard to the pillar or standard 35 to take account of the arcuate path of movement of the ends of the horizontal limb of bell crank lever 64.

The vertical limbs of the bell crank lever 64 are pivotally connected by a pin at 71 with a lug 73 upstanding from a plate 97 bolted to the end of a link 72 which is arranged for horizontal reciprocation under the influence of a cam 98 on shaft 17. Cam 98 is formed by two rigidly connected profile plates 98' and 98'' and two rollers 72' and 72'' on link 72, each of said rollers engaging with one of said profile plates so that link 72 is always moved positively. A slot 101 in the link 72 engages over a washer 102 surrounding sleeve 17 on shaft 17, Fig. 13, so that link 72 is guided in its movements. When the link 72 is drawn to the left in Fig. 4, the bell crank lever 64 and link 72 are rocked about the pivot 65 to raise the pillar or standard 35 in the sleeve 63. By this means all the parts supported by the pillar or standard 35 including the record engaging arms 25 and 26 and the record engaged thereby are raised, and the central aperture of the record is freed from the turntable spindle. At the same time the pin 59 is disengaged from the cupped end of lever 60, and member 37 from the ball end of lever 45. A spiral tension spring 74 is provided between the point of connection 71 of the bell crank lever 64 with the link 72, and a fixed point on the machine to reduce the amount of work called for from the machine motor 3 through the shaft 17 in raising the pillar or standard 35 and the parts carried thereby.

The fixed point on the machine may be conveniently formed by a pin 107 on a bracing bar 108 extending between the brackets 66 and a further bracket 109 secured to the underside of the base plate 1, this bracing bar 108 also engaging the lower end of the camshaft 17 to furnish rigidity.

The record having been raised from the turntable 5 in the manner described above, it is next swung laterally from above the turntable 5 to a position where space is afforded for the turning over of the records and this is effected by rotating the pillar or standard 35 in the sleeve 63.

On the lower end of the pillar or standard 35 is fixedly mounted a ring 79 having a radially extending arm 80 on the end of which is carried a vertical rod 81. This rod engages in an aperture in the end of a horizontal link 82 also movable under the influence of a further cam 99 on the shaft 17.

This cam 99 is formed by two fixedly connected profile plates 99' and 99'' (Fig. 14) and rollers 82' and 82'' on link 82, each of which engage with one of these plates so that the link 82 is always moved positively. A slot 103 in link 82 engages over camshaft 17 and the link is thus guided during its movements.

The profile plate 99' is furnished with a cutaway as shown at 104 (Fig. 14) in which is mounted 10 a short stiff spring 105, the free end of which projects outwards beyond the edge of plate 99' and a corresponding cutaway 106 is formed on the edge of plate 99''. When the cam 99 is in the appropriate position, this spring 105 engages 15 roller 82'' on link 82 in such a manner as to tend to urge the link to the left in Fig. 14 to a somewhat greater extent than would be the case if the edge of profile plate 99' were continuous. The purpose of this arrangement will be described 20 later on. The rod 81 is capable of sliding vertically in the aperture in the end of link 82 to permit the free vertical movement of pillar or standard 35 to which the arm 80 carrying rod 81 is connected. A pair of resilient pads 84 is supported in the machine in a position such that the link 82 is guided between them during its movements, so that the necessary limited lateral movements of the link necessitated by the arcuate path of movement of rod 81 as it moves between the positions indicated in Figs. 3 and 4 to rotate 25 the pillar or standard 35, are permitted.

The pillar or standard 35 having been rotated to bring the parts supported thereby including 30 the record to a position to one side of the turntable as indicated by the horizontal position shown in full lines in Fig. 3, the reversal of the record is next effected.

The reversing movements are imparted to the sleeve 29 within the barrel like member 34, carrier 19 and record engaging arms during an up and down movement of the pillar or standard 35.

At the rear end of the rotatable sleeve 29 in the barrel like member 34 is rigidly fixed a toothed wheel 85. On a pair of upstanding supports 86, 87 on the baseplate of the machine are mounted a pair of toothed racks 88, 89, which are spaced apart a distance which permits the toothed wheel 85 to roll on either rack 88 or rack 89.

To reverse the record, the pillar 35, while in the swung out position, is lowered by the rocking of bell crank lever 64 as permitted by link 72 and the cam 99 controlling said link, and during this lowering movement wheel 85 rolls on rack 88. Sleeve 29 together with carrier 19, arms 25 and 26 and the record are rotated in the bearings 32 and 33 in the barrel like member 34 until when the pillar or standard 35 reaches its lowermost position, these parts have been turned through 60 an angle of 90° into the vertical position indicated in full lines in Fig. 3. During this lowering movement the high part of cam profile plate 99'' is in contact with roller 82' on link 82 and wheel 85 is therefore maintained in mesh with rack 88. As wheel 85 approaches the lower end of rack 88, the spring 105 on cam plate 99' comes into contact with roller 82'' on link 82 and the spring is so loaded that as roller 82' subsequently moves from the high part of cam plate 99'' into the cutaway 106 the link 82 is urged suddenly downwards in Fig. 14 and thereby pillar 35 is rotated slightly in a counter-clockwise direction looking in the direction of Fig. 2 to move wheel 75 85 out from engagement with rack 88 and into

firm though yielding contact with rack 89. The pillar or standard 35 is now raised by the rocking of bell crank lever 64, and sleeve 29 and the parts carried thereby including the record are rotated through a further 90° through the engagement of wheel 85 with rack 89 during the rising movement. Turning over of the record is thus completed.

A spring plunger 90 is carried in an aperture in the body of the barrel like member 34 and 10 this member engages with its lower end against flats 91 formed on the surface of the sleeve 29 to ensure that the sleeve 29 comes to rest in a position where the record is horizontal.

The return of the record to the playing position is effected by a reversal of the sequence of movements, described above as taking place preparatory to the reversing movement.

Link 82 is drawn to the left in Figs. 5 and 11 to rotate the pillar or standard 35 to bring the arms 25, 26 to a position where the record held thereby is suspended over the turntable. When this position is reached, link 72 moves to the right in Figs. 4 and 11 to permit bell crank 64 to rock and thereby lower the pillar or standard 35. During this movement the record is placed on the turntable with its central aperture over the top of the turntable spindle 4 and the now lowermost end of pin 59 engages in the cup shaped end of lever 60 while the formerly uppermost end of the apertured member 37 engages with the ball on the end of lever 45. Lever 60 is now rocked from the position shown in Fig. 3 to that shown in Fig. 5 by a thrust imparted to link 62 from cam 94 and the rod 36 drawn from within sleeve 29. During these movements lever 45 remains stationary in the position shown in Fig. 3 and in consequence member 37 does not move from the position shown in the upper half of Fig. 6, the rod 36 sliding through said member 37. As rod 36 moves from within sleeve 29, the links 57 connected therewith are moved to swing the links 56 and to draw on the bars 52 to partially straighten the corrugated springs 50. The gripping members 48 are thereby permitted to move into the trough shaped members forming the arms 25, 26 under the urge of springs 54 and the record is freed from the grip of the members 48.

The lever 45 is now rocked in a counter-clockwise direction in Fig. 3 under the control of link 47, and cam 94 whereby member 37 is caused to slide from the position shown in the upper half of Fig. 6 to that shown in the lower half of that figure. This movement results in arms 25 and 26 being swung in a horizontal plane away from one another into the position shown in full lines in Fig. 1. With the arms 25, 26 in this position, the operation of the reversing mechanism is complete and the record is ready for reproduction of the selection on that side of the record which was formerly underneath.

While in the example described and illustrated the turning over movement of the record takes place partly during a lowering movement of the carrier and partly during a rising movement of the carrier, it will be clear that by utilizing a rack of sufficient length, the record may be turned through 180° during movement of the carrier in one direction up or down. Similarly, 70 by providing for a lifting movement of sufficient extent for the carrier, a record can be reversed without the necessity for swinging the record laterally with regard to the turntable. Again, the carrier, instead of moving up and down as in the 75

case described in directions at right angles to the plane of the turntable may move in directions which lie obliquely to the plane of the turntable.

We claim:—

5. 1. In an automatic phonograph including a turntable, record reversing mechanism comprising record engaging members, means for causing said members to grip a record on said turntable and initially elevate the same, means for moving 10 said members and record to a position clear of said turntable, means for subsequently elevating and lowering said record engaging members and record when in said clear position, means for rotating said engaging members and record through an angle of 180° during the raising and lowering 15 movement of said engaging members to reverse said record, and means for returning said engaging means and record to said turntable to present the reverse side 20 of the record for reproduction.

2. In an automatic phonograph including a record tablet and a support therefor, record reversing mechanism comprising means for removing the record from said support, means for moving said first named means and record to a position clear 25 of said support, means for vertically reciprocating said first named means and record in said clear position, means for reversing said first named means and record while in said position during 30 the reciprocatory movement thereof, means for returning said first named means and record to a position over said support, and means for lowering said first named means whereby to deposit said record on said support in said reversed position.

3. In an automatic phonograph including a turntable, record reversing mechanism comprising a vertically reciprocable standard, record engaging arms carried by said standard, means for causing said arms to engage a record on said turntable, means for shifting said standard laterally to a position clear of said turntable when in a raised position, means for reciprocating said standard in said clear position, and means for 40 rotating said arms and record through an angle of 180° during the reciprocatory movement of said standard.

4. In an automatic phonograph including a turntable, record reversing mechanism comprising means for gripping a record on said turntable, means for elevating said gripping means and record above said turntable, means for moving said gripping means and record laterally to a position clear of said turntable, means for reversing said gripping means and record simultaneously with the lowering and subsequent elevation thereof in said clear position, means for subsequently moving said gripping means and record laterally to a position over said turntable, means for lowering said gripping means and record to deposit said record on said turntable, and means for releasing said gripping means.

5. In an automatic phonograph including a turntable, record reversing mechanism comprising means for removing a record from the turntable, means for moving said first named means and record to a position clear of the turntable, means for elevating and lowering said first named means and record when in said clear position, 60 means for rotating said first named means and record through an angle of 180° during the raising and lowering movement of said first named means to reverse said record, and means actuating said first named means to deposit said record on said turntable.

6. In an automatic phonograph including a turntable, record reversing mechanism comprising record engaging means, means for causing said engaging means to grip a record on said turntable, means for moving said engaging means and record to a position clear of said turntable, means for elevating and lowering said engaging means and record when in said clear position, means for rotating said engaging means and record through an angle of 180° during the raising and lowering 10 movement of said engaging means to reverse said record, and means for returning said engaging means and record to said turntable to present the reverse side of the record for reproduction.

7. In an automatic phonograph, a record transfer mechanism comprising a carrier, record gripping arms pivoted to said carrier, a reciprocable standard for pivotally supporting said carrier, cam and lever means for reciprocating said standard longitudinally and for rotating it about its 20 axis, and means for rotating said carrier and record gripping arms through an angle of 180° during the reciprocatory movement of said standard.

8. In an automatic phonograph, a record transfer mechanism comprising a carrier, record gripping arms pivoted to said carrier, resilient record contacting means carried by said arms, a reciprocable standard for pivotally supporting said carrier, means for reciprocating said standard longitudinally and for rotating it about its axis, and means for rotating said carrier and record gripping arms through an angle of 180° during the reciprocatory movement of said standard.

9. In an automatic phonograph, a record transfer mechanism comprising a carrier, record gripping arms pivoted to said carrier, resilient record contacting means carried by said arms, a reciprocable standard for pivotally supporting said carrier, cam and lever means for imparting a longitudinal and a rotational movement to said pillar or standard of and about its axis, and means for rotating said carrier and record gripping arms through an angle of 180° during the reciprocatory movement of said standard.

10. In an automatic phonograph, a record transfer mechanism comprising a carrier, a plurality of two part record engaging arms pivoted to said carrier and friction gripping means on adjacent sides of the parts of each arm, a vertically reciprocable standard for pivotally supporting said carrier, means for actuating said arms and gripping means, means for reciprocating said standard longitudinally and for rotating it about its axis, and means for rotating said carrier through an angle of 180° during the longitudinal reciprocatory movement of said standard.

11. In an automatic phonograph including a turntable, a record reversing mechanism comprising a pillar or standard, means for reciprocating said standard, a carrier rotatably mounted on said standard, record engaging arms pivoted to said carrier, said arms being provided with resilient means for gripping a record, said carrier being further provided with a toothed wheel 60 adapted to cooperate with a rack disposed adjacent said standard for reversing said carrier during a reciprocating movement of said standard.

12. In an automatic phonograph, a record reversing mechanism comprising a pillar or standard, means for elevating and lowering said standard, a carrier rotatably mounted on said standard, record engaging arms pivoted to said carrier, said carrier being further provided with a toothed wheel 70 adapted to cooperate successively with a 75

- pair of racks disposed adjacent to said standard during movement of the standard in two directions to reverse the position of the carrier.
13. In an automatic phonograph, a record reversing mechanism comprising a pillar or standard, means for moving said standard both longitudinally and rotatably about its axis, a bearing mounted in the upper end of said standard, a carrier rotatably disposed in said bearing, a toothed wheel secured to said carrier, said wheel being adapted to cooperate successively with a pair of rack members disposed adjacent to said standard during the longitudinal and rotary movement of said standard to reverse the position of said carrier, and a plurality of record engaging arms pivoted to said carrier.

14. In an automatic phonograph, a record transfer mechanism comprising a carrier, a plurality of two part record supporting arms having friction gripping members on adjacent sides of the parts constituting each arm, pivoted to said carrier, a standard for supporting said carrier, cam and lever means for longitudinally and rotatably moving said standard of and about its axis, and means for effecting independent movement of said arms and gripping members, said last named means being automatically connected and disconnected from said arms and gripping members as said carrier moves into or out of the position it occupies during record reproduction.
